UNITED STATES PATENT OFFICE.

JOSEPH LOUIS KIEFFER, OF MONTREAL, CANADA.

TAKE-UP MECHANISM FOR SHOE-SEWING MACHINES.

SPECIFICATION forming part of Letters Patent No. 729,604, dated June 2, 1903.

Original application filed May 1, 1902, Serial No. 105,493. Dividized and this application filed October 20, 1902. Serial No. 127,967. (No model.)

To all whom it may concern:

Be it known that I, JOSEPH LOUIS KIEFFER, a subject of the King of Great Britain, residing at Montreal, in the county of Hochelaga, in the Province of Quebec, Canada, have invented certain new and useful Improvements in Take-Up Mechanism for Shoe-Sewing Machines; and I do hereby declare that the following is a full, clear, and exact description of the invention, such as will enable others skilled in the art to which it appertains to make and use the same.

My invention relates to improvements in shoe-sewing machinery of that class technically known as the "outsole-stitcher"—that is to say, to a machine adapted to sew the sole of the shoe to the welt thereof, and to form a lockstitch by means of two interlocking threads, which are looped together in the well-known manner of sewing-machines.

The principal object in view of the invention herein described is to provide an improved arrangement of the parts of the take-up mechanism used on this class of machinery, and to avoid a difficulty of the machine at present in use which has been caused by the interference of the auxiliary takeup-arm with the motion of one of the cam-levers of the machine, or rather of the gear-segment carried by that lever, which in certain adjustments had so far a downward swing that it was caused to strike against the said auxiliary takeup-arm and would break the thread by so doing, or in some cases the blow would even suffice to break the auxiliary arm itself.

A further object of my invention is to provide means for resiliently supporting said auxiliary takeup-arm in order to tighten the thread to the requisite extent, while at the same time preventing any liability of its becoming broken.

To these ends my invention consists in the improved conformation of the auxiliary takeup-arm, whereby more room is obtained for the oscillation of the machine cam-levers, this conformation of the said arm being a U or J shape, the short arm of which projects downwardly and the long arm upwardly through and between the two rollers of the main take-up-arm; and a spring-support is provided which presses outwardly against the arm and

holds it in raised position, at the same time permitting it to yield upon the drawing up of the slack thread, whereby to enable an adjustable tension to be brought on the arm 55 without breaking the said thread.

My invention further includes a particular and improved form of thread-locking device for preventing the back motion of the thread at any time, and in particular during the action of the pull-off motion, which thread-locking device is mounted on the shaft of the auxiliary takeup-arm.

My invention further consists in the particular construction and combination of parts 65 hereinafter to be described and which will appear from the detailed description herein-after given, and are more particularly pointed out in the accompanying claims.

My invention is illustrated in the accompanying drawings, wherein—

Figure 1 is a side elevation from the left side of the parts of an ordinary outsole-stitcher concerned in the operation of my takeup mechanism, the latter being shown 75 fixed thereto in position and the parts coöperating therewith. Fig. 2 is a plan view of the same. Fig. 3 is a front-to-rear sectional elevation taken on the line 33 of Fig. 2. Fig. 4 is a front elevation of the parts shown in 80 Fig. 3, parts being broken away. Fig. 5 is a central plan section taken on the line 55 of Figs. 3 and 4.

The same numerals of reference denote like parts in all the figures of the drawings. 85

All those parts of the machine which do not concern the invention herein described are omitted from the drawings for the sake of clearness, and to understand the general construction of the machine reference may 90 be had to my original application, Serial No. 105,493, filed May 1, 1902, of which this is a division.

In general, 6 designates the main frame of the machine, comprising a base-plate 7, secured to the pedestal 8 and having an up-standing arm 9, which supports the pivot-pin 10 of the takeup-lever 11, this last being operated by the cam-groove 12 in the cam-block 13, keyed to the main shaft 14 of the machine. 95

At the rear of the machine is, as usual, a bracket-arm 15, which supports the pivot-bolt

16 of the tension-wheel 17, which latter is provided with any suitable friction-disk 18, frictionally pressed against it by the spring 19, which is adjustable by the handle 20 of the 5 screw-spindle 21, which enters the threaded socket on the end of the pivot-bolt 16. The tension-wheel 17 has a groove 22 in which the thread runs, the latter being wound around said wheel, so as to prevent it from being 10 drawn frictionally thereover. All this mechanism as thus far described forms no part of my present invention.

The tension-wheel 17 is adapted to be locked against turning during the operation of the 15 takeup mechanism by the locking-lever 23, which has a lug or projection 24 projecting into the groove 22 of the tension-wheel, and which is operated by a suitable cam mounted on the main shaft of the machine to depress 20 the lug 24 against the groove of the tension-wheel during the motion of the takeup mechanism and to release it at other times.

The cam-groove 12, which operates the takeup-lever 11, has a sharp peak 25 at one 25 point thereof, which causes the lever to be suddenly thrown upwardly and back again, this operation taking place just as the thread-loop is passed over the bobbin. At its forward end the takeup-lever has pivoted there- 30 to, as shown, a long depending link 26, which has a slight bend 27 near its lower end to enable it to avoid the stitch-forming and feed mechanism and is connected at its lower end by a pivot-screw 27^a to the main takeup-arm 35 35 28 at a short distance forwardly of its pivot upon the bolt 29, which is of the form illustrated in Fig. 5. The bolt 29 has a shoul- 40 dered shank composed of an enlarged portion 30 and a reduced portion 31, the former of 45 which forms the pivot for the hub 32, of the takeup-arm 28, the bolt having a head 33, which serves to confine the hub 32, and hav- 50 ing the shoulder of the shank 31 set against a projecting lug 34, formed on the base-plate 55 7 of the frame, and the bolt 29 is clamped in position in the mauner shown in Figs. 4 and 5 and which will be presently referred to. The takeup-arm 28 has a slight angular bend at the point where it joins the link 26 and has 60 also at this point a grooved thread-roll 35 and at its outer end a similar grooved thread-roll 36, pivoted, respectively, upon the pivot- 65 screws 27^a and 37. It will thus be seen that the cam 12 is adapted to give the takeup-arm 11 a swinging movement upwardly through an arc somewhat greater than ninety degrees.

With the takeup-arm cooperates an auxiliary arm 38, which takes the place of a bracket-arm formerly projecting horizontally from the 60 base-plate 7; but, as herein shown, the arm is of U or J shape, having the shorter arm pivoted upon the bolt 29, or rather upon a short sleeve 39, loosely mounted upon the shank portion 31 of the bolt, which sleeve is adapted 65 to be clamped in position with the other parts and is therefore made slightly longer than the hub 40 of the auxiliary arm, Fig. 5, in or-

der to enable the arm to have a free pivotal motion thereon. The auxiliary arm 38 passes first downwardly and beneath the takeup-arm 28, as shown in Fig. 1. It thence passes upwardly between the two thread-rolls 35 and 36 and carries at the upper end thereof a grooved thread-roll 41, which is mounted on the pivot-screw 42 and has an arched shield 75 43, through the eye of which and over the thread-roll the machine-thread 44 is adapted to be passed. The auxiliary arm 38 is further provided near its base with a compression-spring 45, which is supported in shallow apertures bored in the opposing faces of the auxiliary arm and the frame, as shown in Fig. 1, and which resiliently supports the auxiliary arm in its raised position, so as to hold the thread-roll 41 in opposition to the downward motion of the thread-rolls 35 and 36. Furthermore, the hub 40 of the auxiliary arm has a backwardly-extending tongue 46, (best shown in Figs. 2 and 3,) which tongue is adapted to rest normally upon the flat surface of the base-plate 7, but to be raised slightly when the auxiliary arm is depressed by the tension of the thread on the roller 41. The amplitude of movement of the auxiliary arm in this instance is accurately adjustable 95 by a set-screw 47, which is seated in a threaded socket in the end of the tongue 46.

At the left of the auxiliary arm 38 and upon the reduced portion 31 of the bolt 29 is loosely mounted a drum 48, which is held in position by a sleeve 49, interposed between the drum 48 and the shank 31, and has a collar 50 at the outer end thereof, which cooperates with a suitable groove formed in the drum 48 and prevents it from shifting laterally thereon. The sleeve 49 is adapted to be clamped fast to the bolt in stationary position by means of the tightening-nut 51, and is therefore made slightly longer than the drum 48 in order to permit the free play of the latter 105 thereon, as shown in Fig. 5. At its end adjacent to the auxiliary arm 38 the drum 48 carries a sheave 52, having a deep V-shaped groove 53 therein, which is adapted to receive and to securely hold the thread, which is wound in a single turn around the sheave 52 and in the groove thereof, before passing to the thread-rolls 35, 41, and 36. The object 110 of this drum and sheave is to prevent back motion of the thread and to secure it against being drawn backwardly by the motion of the pull-off mechanism, and to this end I provide on the outer or left-hand end of the drum 48 a ratchet-wheel 54, with the teeth of which 115 engages a pawl 55, mounted upon a pivot-screw 56, carried by a short forwardly-projecting arm 57, which is mounted upon the end of the shank 31 of the bolt 29, as clearly 120 shown in Figs. 2 and 5. The arm 57 has at its end a small wire spring 58, secured thereto by a screw 59, which spring is adapted to press against the under side of the pawl and hold it in engagement with the teeth of the ratchet-wheel 54, it being understood that 125 130

these teeth are pointed in a left-hand direction, as seen in Fig. 1, whereby to prevent the backward rotation of the drum 48. The bolt 29 and the sleeves 39 and 49 thereon, together with the arm 57, are all securely clamped fast in rigid position by means of the nut 51, and the arm 57 is thus prevented from being rotated by the reaction of the ratchet-wheel, while at the same time it may be

readily adjusted in angular position.

In the operation of the device (which is in connection with either a thread-hook or shuttle mechanism for passing the machine-thread over the bobbin) the takeup-lever 11 is given a quick swing upwardly by its cam, thus swinging the takeup-arm 28 upwardly and releasing enough thread to permit of the drawing out of the thread-loop to pass over the bobbin; and as soon as this has taken place the takeup-lever is swung downwardly again by the takeup-cam, and the takeup-arm 28 is likewise swung downwardly, drawing the loop down over the bobbin and finally pulling the loop taut. At the end of the downward swing of the takeup-arm or at any point of its downward movement, to prevent any sudden jar upon the thread and breaking of the same, the yieldable mounting of the auxiliary arm 38, effected by the spring 45, causes the auxiliary arm to yield to a slight extent as soon as the stitch has become taut, whereby the thread is prevented from becoming broken when the takeup-arm moves downwardly to take up the thread-loop. At the same movement the thread-lock lever is brought into action by its cam, and, pressing in the groove 22 of the tension-wheel, prevents the latter from rotating, in order to keep the takeup-arm from drawing new thread from the wax-pot.

The locking-sheave 52 is operative at all times to prevent any back motion of the thread, but especially to resist the backward pull exercised upon it by the pull-off motion, which draws the thread from the tension-wheel.

While I have shown in the accompanying drawings the preferred form of my invention, it will be understood that I do not limit myself to the precise form shown, for many of the details may be changed in form or position without affecting the operativeness or utility of my invention, and I therefore reserve the right to make all such modifications as are included within the scope of the following claims, or of mechanical equivalents to the structures set forth.

Having thus described my invention, what I claim as new, and desire to secure by Letters Patent, is—

1. In a shoe and leather sewing-machine of the lockstitch type, the combination of a pivot-bolt, a grooved sheave mounted to turn loosely thereon and adapted to hold the thread against frictional movement thereover, a ratchet-wheel secured to said sheave, an arm mounted on said bolt and clamped thereto, a

pawl carried by said arm and engaging with said ratchet-wheel to prevent backward rotation of said sheave, and a takeup-arm 75 loosely mounted on said bolt.

2. In a shoe and leather sewing-machine of the lockstitch type, the combination of a pivot-bolt mounted on the frame of the machine, a sleeve mounted on said pivot-bolt, a pawl-arm also mounted on said pivot-bolt, a nut adapted to clamp said sleeve and pawl-arm in position on said bolt, a pawl carried by said pawl-arm, a drum loosely turning on said sleeve and having thereon a grooved 80 thread-sheave, a ratchet-wheel engaging with said pawl, and a takeup-arm loosely mounted on said sleeve.

3. In a shoe and leather sewing-machine, the combination of a takeup-arm pivotally 85 mounted at one end, a pair of thread-rolls carried at different points of said arm, a recurved auxiliary arm pivotally mounted upon the same axis as said takeup-arm and arranged to project below said takeup-arm and 90 upwardly between the rolls carried thereby, and a thread-roll mounted on the end of said takeup-arm.

4. In a shoe and leather sewing machine, the combination of a takeup-arm pivotally 95 mounted at one end, a pair of thread-rolls carried at different points of said arm, a recurved auxiliary arm pivotally mounted upon the same axis as said takeup-arm and arranged to project below said takeup-arm and 100 upwardly between the rolls carried thereby, a thread-roll mounted on the end of said takeup-arm, and a spring arranged to resiliently maintain said auxiliary arm in an upwardly-pressed position.

5. In a shoe and leather sewing machine of the lockstitch type, the combination of a takeup-arm pivotally mounted upon a horizontal axis, a pair of thread-rolls carried thereby at different distances from said axis, 110 means for oscillating said takeup-arm, a J-shaped auxiliary arm mounted on the same axis as said takeup-arm and extending below the latter and up between the rolls thereof, a thread-roll carried at the end of said takeup-arm, a spring arranged to press against the base of said auxiliary arm to hold it in upwardly-projected position, and a tongue projecting backwardly from the hub of said auxiliary arm and confined so as to have a limited adjusting movement.

6. In a shoe and leather sewing-machine, the combination of a pivot-pin mounted in the frame of the machine, a takeup-arm pivotally mounted on said pin and having a pair 125 of thread-rolls thereon, means for oscillating said takeup-arm at the proper times, an auxiliary arm pivotally mounted on said pivot-pin and arranged to extend downwardly below and then upwardly between said rolls, a 130 third thread-roll mounted on the end of said auxiliary arm, a resilient support for said auxiliary arm, a drum mounted to turn on said pivot-pin, a tension-sheave having a V-

shaped groove and a ratchet-wheel formed integrally with said drum, and a pawl adapted to engage the teeth of said ratchet-wheel to prevent the same from having a backward movement, whereby the machine-thread is arranged to be carried around said tension-sheave and subsequently around one of said takeup-rolls, the third said takeup-roll and the other of said first-mentioned rolls in order, substantially as described.

7. In a shoe and leather sewing machine of the lockstitch type, the combination of a boss projecting from the frame of the machine at the lower front portion thereof, a shouldered pivot-pin mounted in said boss, a takeup-arm pivotally mounted on said pin, a takeup-link pivotally connected to said takeup-arm, a takeup-lever connected to the opposite end of said link, a takeup-cam adapted to operate the said lever and mounted on the main shaft of the machine, a pair of thread-rolls carried by

said takeup-arm, a recurved auxiliary arm pivotally mounted on said pivot-pin and extending downwardly and then upwardly between said thread-rolls, a third thread-roll 25 carried by the end of said auxiliary arm, a drum having a tension-sheave and a ratchet-wheel thereon also pivotally mounted on said pin, a collared sleeve interposed between said drum and auxiliary arm and the pivot-pin, a 30 pawl-bar carried by the end of said pivot-pin, a nut on the end of said pivot-pin clamping the pawl-bar and said sleeve in position thereon, and a spring-pressed pawl carried by said pawl-bar and arranged to engage the 35 teeth of said ratchet-wheel.

In witness whereof I have hereunto set my hand in the presence of two witnesses.

JOSEPH LOUIS KIEFFER.
